UNITED STATES PATENT OFFICE.

FRANK E. STEBBINS, OF WASHINGTON, DISTRICT OF COLUMBIA.

DRAFT AND BUFFING GEAR FOR CARS.

1,168,974.

Specification of Letters Patent. Patented Jan. 18, 1916.

Application filed May 3, 1911. Serial No. 624,749.

To all whom it may concern:

Be it known that I, FRANK E. STEBBINS, a citizen of the United States, residing at Washington, District of Columbia, have invented certain new and useful Improvements 5 in Draft and Buffing Gear for Cars, of which the following is a specification.

The object of the invention is the provision of an improved draft and buffing gear for cars which shall be comprised of relatively few parts that can easily and quickly be assembled and also disconnected with equal facility and without the use of special tools or appliances whereby repairs when necessary can be made in any place on the road and outside a shop; which shall be so constructed that it will withstand the severe shocks of service without injury; which shall have the movable parts so combined that they will maintain their normal relative positions and transmit strains equally to both sills of the car underframe; and in which "lost motion" may readily be taken up or the parts easily be re-adjusted one to another or to each other when displaced 25 through wear or otherwise.

The invention consists generically in a gear having the draft sills or beams united by a fixed abutment, a movable abutment in front of the fixed abutment, cushioning means between the two abutments, means for supporting the cushioning means so displacement will not take place during the action of drawing and buffing, a draw bar 30 with a slotted shank, and a U-shaped yoke having arms disposed in vertical planes at the sides of the movable abutment and cushioning means and its rear part uniting the arms located next to the fixed abutment, the 35 free ends of said arms being connected to the draw bar by a key passed through the draw bar shank and the ends of the said yoke, the arrangement being such that in buffing the draw bar and key may move rearwardly relative to the yoke and in drawing that the draw bar and key may move forwardly, the cushioning means and movable follower at the same time being limited in their forward movements.

50 Further, it consists in the combination with such a gear of separate adjustable plates for taking up "lost motion," or, in other words, for adjusting the yoke in a permanent rearward position when the slots in 55 the free ends of the yoke become elongated by wearing away of the metal in service.

Further, it consists in certain novelties of construction and combinations and relative arrangements of parts as herein set forth and claimed.

The accompanying drawings illustrate 60 four examples of the physical embodiment of the invention, the parts being constructed, arranged and combined according to the best modes of procedure I have so far devised 65 for the purpose.

Figures 1, 2 and 3 show the first example; Fig. 1 being a vertical longitudinal section in elevation of Fig. 2, which Fig. 2 is a top plan view, and Fig. 3 a cross section on a reduced scale of Fig. 2 on line $x-x$. Figs. 4, 5 and 6 show the second example; Fig. 4 being a vertical longitudinal section in elevation of Fig. 5, which Fig. 5 is a top plan view, and Fig. 6 a cross section on a reduced scale of Fig. 5 on line $y-y$. Figs. 7 and 8 show the third example; Fig. 7 being a vertical longitudinal section of Fig. 8, which latter is a top plan view. Figs. 9, 10 and 11 show the fourth example; Fig. 9 being a vertical longitudinal section of Fig. 10, which latter is a top plan view, and Fig. 11 a cross section on a reduced scale on line $z-z$ of Fig. 10.

To enable those skilled in the art to make 85 and apply and use the gears the following description is given supplemental to the disclosure by the drawings.

The combined parts generically common to all of the examples are: the metallic channel center sills 1 suitably spaced apart with their webs in vertical planes; the channel end sills 2 each with part of the web and flange removed to form an opening for the draw bar; the carry irons 3 for supporting 90 a draw bar; the draw bars 4 each provided with a horizontal slot 5 for receiving a key; the slots 6 in the webs of the channel sills; the slotted cheek plates 7 secured by rivets to the channel sills and with the slots in line 100 with the said slots in the webs of the sills; the fixed cast metal abutments 8 each comprising a body portion 9 with two horizontal holes 10, 10 one above the other, vertical perforated flanges 11, 11 at each end of the 105 body portion and of suitable dimensions through which the perforated webs of the sills are passed rivets 12, and the bottom horizontal flanges 13 through each of which and a lower flange of a channel sill are 110 passed rivets 14, all as shown; the draft yokes 15 each of a general $\square$ shape in

one or more pieces so as to pass back of the cushioning means and each of the two free ends provided with a slot 16; the keys 17 each located within the slots through the 5 sills, cheek castings, yoke, and in the draw bar slot; the movable abutments 18 each located in a vertical plane at the rear end of a draw bar, each movable abutment being provided with two rods or bars 19, 19 one above 10 the other projecting from the rear vertical surface of the said abutment and the ends of the rods movedly supported within the holes 10, 10 of the fixed abutment; the helical springs 20 one disposed above the other 15 and through which the rods 19, 19 are passed; and the adjusting plates 21 preferably perforated and supported on the rods.

In each of the examples the key frictionally engages the metal bounding the slot 20 in the draw bar so the key will move with the draw bar, and the slots in the webs of the sills and in the cheek plates are elongated or open each side of the ends of the keys so they can freely move forwardly in 25 drawing and rearwardly in buffing a suitable distance, depending upon the required draw bar travel. The keys engage the metal at the front ends of the slots in the yokes, but the slots are open at the rear edges of 30 the keys (see dotted lines) so that in buffing the keys may move rearwardly while the yokes remain stationary.

In examples one and four the yokes are formed integral and wider at their closed 35 or united ends than at their free ends and provided with holes 22, 22 through which the rods 19, 19 pass, the said rods thus supporting the yokes in proper positions.

In examples two and three perforated 40 follower plates 23 are present, the rods 19 being passed through the perforations therein and supporting them at the rear ends of the springs.

In the second example the fixed abutment 45 is cast with a recess 24 to receive the rear end of the yoke and the yoke is located between the two rods 19, 19, the lower one supporting and maintaining the rear end of the yoke in alignment.

In the third example the yoke consists of 50 two side bars 15', 15' located outside the webs of the sills and with their rear ends slotted to receive the ends of a key 25 passed through an open slot 26 formed in 55 the fixed abutment and the elongated slots 27 formed in the webs of the sills adjacent to the abutment, the said two bars and the key 25 constituting a U-shaped yoke comprised of three pieces, allowing of their 60 union, and having the same functions as the yoke of the other three examples. The front edge of the key engages the rear surface of the follower plate 23, as shown, so the forward movement of the key will advance the plate in drawing.

In examples one, two and three the rods or bars 19 may be provided with heads 28 seated within recesses in the movable abutments; preferably the rods are cast in the metal of the movable abutments in a well known way to form rigid connections therewith. These rods 19 are threaded at their free ends to receive nuts 29 which prevent the forward movement of the rods in drawing. Suitable cushioning elements may be 75 located on the ends of the rods 19 between the nuts and the fixed abutments, as in the first example where a perforated casing 30, perforated yielding material 31 and a perforated follower 32 are disposed on each 80 rod, as shown, or as in the second example where concavo-convex perforated spring plates 33 are located on the rods between the fixed abutment and the nuts.

In example 4 the rods 19, identified by 85 19', 19' to distinguish them, are integral with the movable abutment or secured thereto in casting or otherwise. Their rear ends are movably located within the holes 10, 10 of the fixed abutment 8 and support the 90 cushioning means so the same will not become displaced in buffing or drawing. In this example the movable abutment is shown slotted with a key 34 in the slot and with its ends movably supported within slots 35 in 95 the sills and cheek plates, the said slots being elongated at 36 in the rear of the edge of the key so the key in buffing can move rearwardly a suitable distance. In drawing the key and front abutment are stationary and the yoke slotted at 37 so it can move forwardly relative to the key.

In the third example the movable abutment may have a lug 38 projecting from its front surface and seated within the rear end of the draw bar to aid in holding the movable abutment in alignment with the draw bar. In examples one and two the edges of the movable abutment above the 105 yoke may be extended and engage the top 110 surfaces thereof, as shown in Figs. 3 and 6, thus holding the said abutment in alignment with the draw bar and so it cannot sag.

The means for "taking up lost motion" 115 so-called, or adjusting the positions of the movable elements relative to one another, or to each other, when the slots in the ends of the draft arms become elongated by wear, consists of perforated metallic plates 21 upon the rods 19 at the front and rear or at 120 either front or rear of the rear end of the yoke in the first and fourth examples, and similar plates perforated or otherwise at the front and rear of the follower plates 23 in examples two and three. Should the 125 slots in the ends of the yokes become worn in service or the springs become set in the first and fourth examples so there is an open space between the movable abutment and the rear end of the draw bar, one or more 130

plates may be removed from the rods at the rear end of the yoke and placed in front of the same and directly back of the springs. In the third example, under similar circumstances, a plate or plates must be removed from the rear to the front of a follower plate 23, as is obvious; and in the second example a perforated plate or plates 40, Fig. 4, may be added on the lug 41 projecting from the follower plate in front of the rear end of the yoke.

In practice it is preferable when the gear is assembled to place several plates 21 at the front and rear of the rear end of the yoke, and at the front and rear surfaces of the follower plates 23 in the third example to provide for future adjustments, such as mentioned or others.

The mode of operation is substantially the same in each example. In drawing the draw bar, key and yoke are advanced and the springs compressed, the rods 19 and movable abutment remaining stationary. In the second and third examples the follower plates 23 are also advanced on the rods by the yoke. In buffing the yoke is stationary in examples one and four, and preferably so in examples two and three, while the draw bar, key, movable abutment and rods move rearwardly relative to the fixed abutment, the springs simultaneously being compressed.

The advantages of the invention as embodied in the specific modes illustrated will be appreciated by those skilled in the art, some of which are as follows: The fixed abutment rigidly secures the sills together so they cannot spread and insures that the severe shocks of buffing will be distributed equally to the two sills. The coupler head and draw bar can rock sidewise on curves, especially in the first three examples, and the spring will return both to their normal positions upon entering a tangent from a curve. The movable parts of the gear can easily be assembled and disconnected outside the shops and by a sledge and wrench. The springs are held in alinement by the rods and cannot accidentally become detached, for in the first three examples the rods each 2 $\frac{1}{2}$ " in diameter fill the openings in the springs, and in the fourth example the 2" rods fill the openings in the springs. The yoke, springs, and rods cannot be torn from the fixed abutment, as the elastic limit of the two rods is far in excess of the energy of any jerks to which they may be subjected. Provision is made for taking up "lost motion," the presence of which in a long train of cars often results in the parting of the train. The parts are few in number, simple in construction, and so united that they will maintain their normal relative positions under the strains and shocks of severe service.

What I claim is:

1. The combination in a draft and buffing

gear, of slotted sills united by a fixed abutment; a movable abutment having two rods in connection therewith, their free ends threaded and passed through the fixed abutment; nuts on the rods; helical springs on the rods disposed in a vertical plane between the two abutments; a slotted draw bar; a yoke disposed in vertical planes each side of the movable abutment and back of the springs with its free ends slotted; and a key passed through the slot in the draw bar and slots at the free ends of the yoke and with its ends movably supported within the slots in the sills.

2. The combination in a draft and buffing gear, of slotted sills united by a fixed abutment; a movable abutment having two rods in connection therewith, their free ends threaded and passed through the fixed abutment; nuts on the rods; cushioning means between the nuts and the fixed abutment and supported by the rods; helical springs on the rods disposed in vertical planes between the two abutments; a slotted draw bar; a yoke disposed at the sides of the movable abutment and back of the springs with its ends slotted; and a key passed through the slot in the draw bar, and slots at the ends of the yoke and with its ends movably supported within the slots in the sills.

3. The combination in a draft and buffing gear, of slotted draft members united by a fixed abutment having an opening; a movable abutment; a bar or rod secured at one end to the movable abutment and its free end movably supported within the opening in the fixed abutment; means at the free end of the bar or rod to prevent the withdrawal of the same from the fixed abutment; cushioning means located between the two abutments; a slotted draw bar; a yoke with slotted ends passed around the cushioning means; and a key passed through the draw bar and the slots at the ends of the yoke, the end of said key being movably supported within the slots in the draft members, and the drawbar being movable away from said movable abutment in drawing.

4. The combination in a draft and buffing gear, of slotted draft members united by a fixed abutment provided with a horizontal opening for a rod; movable abutment; a rod independent of the draw bar secured to and movable with said abutment and its free end passed through the opening in the fixed abutment; means at the end of the rod to prevent the withdrawal of the rod from the fixed abutment; springs located between the two abutments and supported on the rod; a slotted draw bar; a yoke with slotted ends passed around the springs; and a key passed through the draw bar and the slots in the ends of the yoke, the ends of said key being movably supported within the slots in the draft members, and the draw bar being

movable away from said movable abutment in drawing.

5. The combination in a draft and buffing gear, of draft members united by a fixed 5 abutment; a movable abutment; rods in connection with the movable abutment and supported by the fixed abutment so they can move rearwardly relative to said fixed abutment; cushioning means at the rear of 10 the movable abutment; a slotted draw bar; a yoke with slotted ends passed around the cushioning means; and a key uniting the draw bar and the ends of the yoke.

6. The combination in a draft and buffing 15 gear, of draft members united by a fixed abutment; a movable abutment; rods in connection with the movable abutment and supported by the fixed abutment so they can move rearwardly relative to said fixed abutment; cushioning means consisting of helical 20 springs between the two abutments and the said rods passed through the same; a slotted draw bar; a yoke with slotted ends passed around the cushioning means; and a key 25 uniting the draw bar and ends of the yoke; the draw bar and yoke being movable relative to said movable abutment in drawing.

7. The combination in a draft and buffing gear, of sills; a fixed abutment uniting the 30 sills; a movable abutment; helical springs between the abutments; rods supported by the fixed abutment secured to the movable abutment and parts of said rods located 35 within the helical springs to maintain said springs in their proper positions; a draw bar; and a yoke passed around the springs and having its ends secured to the draw bar.

8. The combination in a draft and buffing gear, of sills; a fixed abutment uniting the 40 sills; a movable abutment; cushioning means between the two abutments; rods connected to the movable abutment, supporting the cushioning means and having their ends supported by the fixed abutment; a draw 45 bar; and a yoke surrounding the cushioning means and secured to the draw bar.

9. The combination in a draft and buffing gear, of sills; a fixed abutment uniting the 50 sills; a movable abutment; helical springs between the two abutments; rods connected to the movable abutment, passed through the helical springs and having their ends supported by the fixed abutment; a draw bar; and a yoke surrounding the helical springs 55 and secured to the draw bar; said draw bar and yoke being movable relative to the said movable abutment in drawing.

10. The combination in a draft and buffing gear, of sills; a fixed abutment uniting the 60 sills; a movable abutment; cushioning means between the two abutments; rods connected to the movable abutment, passed through the cushioning means and having their ends supported by the fixed abutment; a draw bar; and a yoke having arms with 65

elongated slots surrounding the cushioning means and secured to the draw bar; the rear end of the said yoke having holes through which the rods are passed and by which rods the rear end of the yoke is supported.

11. The combination in a draft and buffing gear, of sills; a fixed abutment with 70 openings uniting the sills; a movable abutment; helical springs between the abutments; rods rigidly secured to the movable abutment and passed through the fixed abutment; and means in connection with the ends of the rods at the rear of the fixed abutment to prevent the forward movement of the said rods and the movable abutment; a draw bar; and means connecting the draw bar with the springs; the draw bar in drawing being movable away from said movable abutment.

12. A movable follower for a draft and buffing gear having two rods independent of the draw bar and secured to the abutment so the rods and abutment always move together uniformly and said rods provided with means for securing the same to an abutment; cushioning means between the movable follower and the abutment; a draw bar; and means for connecting the draw bar with the cushioning means whereby the draw bar can move away from the movable follower in drawing, and move with the movable follower in buffing.

13. The combination in a draft and buffing gear, of sills united by a fixed abutment provided with openings; a movable 100 abutment having two rods with their free ends supported within the openings in the fixed abutment; helical springs on the rods between the movable and fixed abutments; means for preventing the forward movement of the movable abutment in drawing, 105 a yoke surrounding the springs and with its free ends slotted; a slotted draw bar; and a key passed through the slots in the ends of the yoke and the slot in the draw bar.

14. The combination in a draft and buffing gear, of draft members; a rigid abutment uniting the draft members; a movable abutment; springs between the movable and fixed abutments; means for connecting the movable abutment with the fixed abutment whereby the former can move rearwardly relative to the latter; a draw bar; a yoke for connecting the draw bar with the rear ends of the springs; and means 115 for taking up "lost motion."

15. The combination in a draft and buffing gear including a draw bar and draft means, of a fixed abutment; a movable abutment; rods connecting the front abutment 120 with the fixed abutment; cushioning means in connection with the rods; means at the ends of the rods for preventing the forward movement of the rods and the movable abutment; and perforated plates supported by 125 130

the rods for adjusting the movable parts of the gear one relative to another.

16. The combination of draft members, a fixed abutment or abutments on the draft members, a movable abutment, cushioning means at the rear of the movable abutment, a draw bar, means for connecting the draw bar with the cushioning means, and means for taking up "lost motion."

17. The combination with a draft and buffing gear having a slotted draw bar, yoke with slotted draft arms, a key uniting the draw bar and draft arms, cushioning means suitably supported, and means for taking up "lost motion."

18. The combination with a car draft and buffing gear having a slotted draw bar, yoke with slotted draft arms, and a key uniting the draw bar and slotted draft arms said key being fixed in the draw bar and movable in the slots of the arms, of means for taking up the lost motion due to the set of the springs or the wearing away of the metal between the key and the arms.

19. The combination in a draft and buffing gear, of draft beams, a fixed abutment rigidly secured to and between the beams and having an opening therein, a draw bar, a horizontally disposed yoke with arms secured to the draw bar, a movable

abutment, cushioning means back of the movable abutment, a rearward extension carried by the movable abutment passed back of the rear of the yoke and supported within the opening of the fixed abutment, 35 and means for anchoring the said rearward extension to the fixed abutment so the movable abutment cannot advance in drawing, but can move rearwardly in buffing.

20. The combination of slotted draft 40 beams united by a fixed metallic abutment secured to and between the beams, a slotted drawbar, a U-shaped yoke horizontally disposed having its free ends slotted and united by a key of less width than the slots 45 to the drawbar and its rear end normally bearing against the metallic abutment, a movable abutment having a limited rearward movement and supported by a key or bar passed through the same and supported 50 by the draft beams, cushioning means between the fixed and movable abutments, and means for retaining said cushioning means in proper position between the abutments.

In testimony whereof I affix my signature 55 in presence of two witnesses.

FRANK E. STEBBINS.
